UNITED STATES PATENT OFFICE.

JOSEPH ALBERT RONCHETTI, OF WOONSOCKET, RHODE ISLAND, ASSIGNEE, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,120,747.

Specification of Letters Patent. Patented Dec. 15, 1914.

Application filed June 5, 1908. Serial No. 436,746.

To all whom it may concern:

Be it known that I, Joseph A. Ronchetti, a subject of the King of Italy, residing at Woonsocket, in the county of Providence and State of Rhode Island, have invented certain new and useful Improvements in Type-Writing Machines, of which the following is a full, clear, and exact description, such as will enable others skilled in the art to which it appertains to make and use the same.

This invention relates to typewriting machines, and one of the objects thereof is to provide new and improved means for preventing the printing instrumentalities from reaching the platen and for preventing an operation of the spacing mechanism when the carriage has completed a line of writing.

Another object of the invention is to provide an improved form of margin stop block.

Another object is to provide improved means for adjusting the margin stop blocks upon the platen carriage and for conveniently indicating the adjusted positions thereof with respect to the margin rack bar.

A further object of the invention is to provide means whereby the returning movement of the carriage may be arrested without producing noise.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein I have illustrated two of the various possible embodiments of my invention, Figure 1 is a view taken transversely of a typewriting machine, the mechanism constituting the invention being shown in elevation. Fig. 2 is a plan view of a portion of the mechanism shown in Fig. 1, part of the carriage and the top plate of the machine being omitted in the interest of clearness of illustration. Fig. 3 is a sectional view on an enlarged scale taken on line 3-3, Fig. 2, showing the carriage return stop. Fig. 4 is a view in side elevation of a modified form of the margin release mechanism. Fig. 5 is a plan

view of the mechanism shown in Fig. 4, the top plate of the machine being omitted. Fig. 6 is a rear elevation of the mechanism shown in Figs. 4 and 5. Fig. 7 is a sectional view of a portion of Fig. 4, but showing the locking lever in a different position. Fig. 8 is a plan view showing the locking lever in still another position. Fig. 9 is a side elevation of the portion of Fig. 4 showing the margin block released from the rack. Fig. 10 is a front view of the portion of the carriage shown in Fig. 9.

Similar reference characters refer to similar parts throughout the several views of the drawings.

Referring now to the drawings, 1 denotes a portion of the framing of the machine and 2 the center tie-rod, which extends from front to rear of the machine and is provided with a vertically disposed portion or horn 3 which extends upwardly behind the platen carriage 4 to form a rigid backing therefor. The platen roll is shown at 5 and the platen, which is constituted by a thin strip of metal located in front of the platen roll and lying in contact therewith, is shown at 6. The platen carriage 4 in the present instance rides during its letter-spacing movement, or in its return movement to begin a new line of writing, upon a rail 7 which extends longitudinally of the machine.

9 denotes one of the type-bars of the bank thereof, which rests upon a bed supported in the framework of the machine, and is adapted to be projected against the platen by actuating mechanism connected with a key lever.

The universal bar 8 is shown suspended upon links 10, which in turn are suspended upon arms 11 mounted upon a universal rock-shaft 12, which extends longitudinally of the machine and is journaled upon trunnion screws 13 carried by the side walls thereof. The key levers, one of which is shown at 14, rest upon the universal bar and when depressed to effect printing actuate the same and universal rock-shaft.

15 represents a paper table, which is carried by the platen carriage and extends beneath the platen roll, said paper table being provided with an upwardly and rearwardly extending portion 16. Mounted upon said paper table, adjacent the rear edge thereof, is a scale bar 17, said scale bar in the present

2

instance being provided with depending portions 18 disposed behind the paper table, which have longitudinally extending slots 20 for receiving bolts 21, by means of which the scale bar is secured to the paper table. It will be understood that scale bar 17 may be adjusted along the paper table and secured in any desired position by means of the bolts 21.

Upon the platen carriage, behind the paper table, is secured a rack bar 22, said rack bar having vertically disposed or upstanding teeth 23. Extending across the carriage from side to side thereof is a tube 24, having a horizontally extending slot in which the tongued end 25 of the margin stop block 26 is adapted to slide, said slot being of sufficient width to allow the margin stop block 26 to be rocked upward to the position shown in Fig. 9 of the drawings. The margin stop block is provided with teeth 27, which engage with those of the rack, and is held in such engagement by means of a spring 28 fastened as by means of rivets 30 to the margin stop block, the end of the spring engaging underneath the rear portion of the paper table 15. The margin stop blocks 26 are each provided with a finger piece 31 which has an indicator portion 32 adapted, when the margin block is rocked out of engagement with rack 22, as shown in Fig. 9 of the drawings, to be engaged with the edge of the scale bar 17 and to coöperate therewith to indicate the position of the block upon the rack bar 22. By means of this construction, it will be seen that the margin blocks may be swung upward and disengaged from the rack 22 at will, whereupon they may be moved longitudinally to any desired adjusted position, and that the adjusted positions may be readily determined by the operator by means of the indicator 32, which coöperates with the scale 17, springs 28 operating to automatically re-lock the margin blocks to the rack bar.

Referring to the embodiment of the line-locking mechanism shown in Figs. 1 and 2 of the drawings, 33 denotes a locking lever which is carried by a shaft 34, one end of said shaft being journaled adjacent its other end in a bearing 36 formed in the center tie-rod 2. Shaft 34 is provided with a head 37 provided with pivot screws 38 which support the locking lever 33. By means of this construction, it will be seen that the locking lever 33 may be oscillated vertically as well as sidewise or horizontally, the vertical movement being effected through a rotation of shaft 34 and the sidewise or horizontal movement being permitted by the pivotal connection of said lever with the pivot screws 38 of head 37. Lever 33 is provided with an upwardly extending portion 40, which is turned forwardly and interposed in the path of the margin stop blocks 26 and is adapted to be engaged by said stop blocks during the letter feeding or return movements of the platen carriage. The opposite end 41 of the locking lever extends forwardly and terminates in adjacency with a vibratory arm 42, depending from the universal rock shaft 12, as shown in Fig. 2 of the drawings. During the oscillatory movements of the universal shaft 12, arm 42 just 75 clears end 41 of the locking lever 33. When, however, the margin stop block at the right hand side of the machine engages the upper end 40 of lever 33, said lever will be swung sidewise upon its pivotal supports 38 and 80 the end 41 of said lever will be moved into position to intercept the arm 42, thereby preventing any oscillatory movement of the universal rock-shaft 12 and also preventing the universal bar 8 from being depressed by 85 the key levers. It will be seen, therefore, that one end of lever 33 intercepts the carriage and prevents a feeding movement thereof when engaged by the margin stop block, and the other end of said lever prevents an actuation of the universal bar and locks the printing mechanism. Extending forwardly from shaft 34 is an arm 43 which is disposed directly above a rearwardly extending portion 44 of a release lever 45, 95 pivoted upon a stud screw 39, the forward end of which is located at the key board and is provided with the finger key 46. Lever 45 is held in the position shown in Fig. 1 of the drawings by means of a spring 47 connected thereto and to a pin 48 fixed in the framework of the machine. When lever 45 is depressed by the finger of the operator, the extension 44 thereof will lift arm 43 and thereby rotate shaft 34, causing a vertical 100 oscillating movement of the locking lever 33, thereby removing the end 40 of said lever from the path of the margin stop block with which the same has been engaged. The locking lever will thus be free to move sidewise 110 to carry the end 41 thereof out of the path of the vibratory arm 42, to release the printing mechanism from its locked condition. This sidewise movement of arm 43 is effected by means of a spring 49, which is shown in 115 Fig. 4 of the drawings.

In the embodiment of my invention shown in Figs. 4 to 8 inclusive, for the locking lever 33 is substituted a lever 51, which is pivoted to oscillate horizontally upon pivot screws 120 52 supported in the center tie-rod 2. Lever 51 has pivotally attached thereto as at 53 a lever 54, the upper end 55 of which is arranged in position to be engaged by the margin stop blocks in a manner similar to that of the end 40 of lever 33. Lever 51 has a depending portion or tail-piece 56, which is connected by means of a link 57 with an upwardly extending portion 58 of a release lever 60 pivoted at 61 to the side wall of 130

the machine and operable from a position at the key board.

Referring now to Figs. 2 and 3, 62 denotes a casing which is mounted upon the rear portion 3 of the tie-rod, said casing carrying a presser member or plunger 63 which projects outwardly from said casing and is adapted to reciprocate therein. The plunger is provided with a stop piece 64 which engages with the walls of a slot 65 provided in the casing, such engagement limiting the extent of the reciprocal movements of the plunger. Adjacent the inner end of plunger 63 is provided an elastic washer 66, which fits the interior bore of the casing, and adjacent this washer is placed a metal washer 67, both of said washers being retained in position by means of a central pin 68. An adjusting screw 70 is tapped into the casing and carries a washer 71. Between washers 67 and 71 is placed a coil spring 72, which is adapted to be entirely compressed between said washers when the plunger is moved inwardly and to limit the forward movement thereof. At this point, it may be noted that the extent of the compression of spring 72 is less than the distance between two adjacent teeth of the carriage rack, the object of which will be apparent hereinafter. The upper end 40 of the line locking lever 33 is arranged adjacent the end of the plunger and is pressed against said plunger by the left hand margin stop block when the carriage is returned to begin a new line of writing, pressing the plunger within the casing against the tension of spring 72.

Having thus described the construction of each embodiment of my invention disclosed herein, the operation thereof may now be understood: It will be understood that when the carriage reaches a predetermined position near the end of a line of writing, the right hand margin stop block 26, which has been previously adjusted to the desired position, will contact with the end 40 of the line locking lever 33 and move the same horizontally, whereby the end 41 will be moved horizontally to such position as will enable it to intercept the vibratory movement of the arm 42, thereby locking the universal bar and preventing the operation of the type-bars through their connection with the key-levers. When it is desired to effect further writing on the same line, a depression of the margin release lever 45 will through extension 44 lift arm 43, thereby swinging the end 40 of the locking lever 33 from engagement with the margin stop block, whereupon spring 49 will return the locking lever to normal position and a spring 73, connected with the locking lever 33 and with an ear 74 upon the tie-rod 2, will return the upper end 40 of lever 33 to its normal position. The rear faces of

the margin stop blocks are of course beveled so that the end 40 of the locking lever 33 may be automatically moved out of the way when the carriage is returned. The operation of the embodiment of the invention shown in Figs. 4 to 8, inclusive, is substantially similar to that next-above described and will be readily understood from the above description. When the carriage is returned to begin a new line of writing, the left hand margin stop block engaging with the end 40 of the release lever will cause said lever to be projected against the plunger 63, thereby forcing said plunger within the casing. At this point it may be noted that said spring 72 is constructed to entirely collapse against washers 67 and 71, and as the extent of yielding movement of the spring is less than the distance between adjacent teeth of the carriage rack, a proper margin register will be maintained.

It will accordingly be seen that I have provided mechanism well adapted to attain, among others, all the ends and objects above set forth, in a simple yet efficient manner. The line locking mechanism is constituted by comparatively few parts and is extremely simple in construction and operation. Another of the advantages inherent in the present construction is that the margin stop blocks may be conveniently adjusted by the operator without the necessity of looking behind the paper table, since the positions of said blocks are accurately indicated by means of the indicating fingers, which co-operate with the scale bar upon the paper table. The returning movement of the carriage is also effectively cushioned in a manner such that no noise is produced during the operation.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having thus described my invention what I claim as new and desire to secure by Letters Patent is:

1. In a typewriting machine, in combination, a carriage adapted to reciprocate transversely of the machine, adjustable stops carried in the rear of said carriage, a type action, a transversely disposed universal rock shaft positioned centrally of the frame of the machine adapted to be actuated at each actuation of the type action, a member directly connected with said rock shaft adapted to oscillate as said shaft is rocked, and a pivoted lever positioned fore and aft of the machine, one end of which is adapted to coact with one of said adjustable stops at

the rear of the carriage to move the other end into the path of said oscillating member, whereby a subsequent movement thereof is positively prevented.

2. In a typewriting machine, the combination with the platen carriage, and the printing instrumentalities, of a margin stop block mounted upon the platen carriage, a universal rock-shaft actuated by the printing instrumentalities, a vibratory member carried by said universal rock-shaft, a lever disposed longitudinally of the machine and movable about a vertical pivot, having one portion thereof disposed in the way of said margin stop block and adapted to be moved about said pivot when engaged thereby, whereby another portion of said lever will be moved into position to be engaged by said vibratory member, said universal rock-shaft will be locked against oscillation and the printing instrumentalities locked against printing, and means located at the keyboard for removing said lever from engagement with said margin stop block whereby further printing may be effected.

3. In a typewriting machine, in combination, a carriage adapted to reciprocate transversely of the machine, an adjustable margin stop carried in the rear of said carriage, a type action, a transversely disposed rock shaft positioned centrally of the frame of the machine adapted to be actuated at each actuation of the type action, a member directly connected with said rock shaft adapted to oscillate as said shaft is rocked, a pivoted lever positioned fore and aft of the machine, one end of which is adapted to contact with said adjustable stop at the rear of the carriage to move the other end into the path of said oscillating member, whereby a subsequent movement thereof is positively prevented, and key actuated means adjacent the key lever of said type action having an operative connection with said lever adapted to move the same about its support whereby its ends are carried out of operative relation to said stop and oscillating member to permit further action of the type action.

5. In a typewriting machine, the combination with a universal bar, the universal rock shaft pivotally supporting said bar, of a part which is moved by said rock shaft at each operation thereof, a stop adapted to reciprocate with the carriage, a locking member movable about axes at right angles to each other having a portion disposed in the path of travel of said stop and another portion adjacent said part, said locking member, when engaged by said stop, being adapted to be moved into the path of said part whereby said rock shaft is locked against movement, means operable from the keyboard for moving said locking member about one axis out of engagement with said

stop, and spring means adapted to engage said member for restoring the same to normal position whereby further operations may take place.

5. In a typewriting machine, in combination, a plurality of key-levers for actuating the type bars, a carriage, an adjustable margin stop block mounted thereon, a universal bar adapted to be actuated by the key-levers, a universal rock-shaft centrally disposed in the frame of the machine and supporting said universal bar, an arm on said rock-shaft adapted to oscillate at each depression of the key-lever, and a universally mounted locking lever mounted upon a relatively fixed portion of the machine and positioned fore and aft therein having one end adapted to be engaged by said margin stop block and the other end extending toward the center of the machine adapted to be moved into the plane of oscillation of said arm when said locking lever is engaged by the margin stop.

6. In a typewriting machine, in combination, a plurality of key-levers for actuating the type bars, a carriage, an adjustable margin stop block mounted thereon, a universal bar adapted to be actuated by the key-levers, a universal rock-shaft connected with the said universal bar, an arm on said rock-shaft adapted to oscillate at each depression of the key-lever, a universally mounted locking lever mounted upon a relatively fixed portion of the machine and positioned fore and aft therein having one end adapted to be engaged by said margin stop block and the other end adapted to be moved into the plane of oscillation of said arm when said locking lever is engaged by the margin stop, and means adapted to actuate said locking lever to raise the forward end of the same out of the path of travel of said arm simultaneously with the rearward movement of the end engaged by the margin stop block, thereby unlocking the printing mechanism.

7. In a typewriting machine, in combination, a plurality of key-levers for actuating the type bars, a carriage, an adjustable margin stop block mounted thereon, a universal bar adapted to be actuated by the key levers, a universal rock-shaft connected with the said universal bar, an arm on said rock-shaft adapted to oscillate at each depression of the key-lever, a universally mounted locking lever mounted upon a relatively fixed portion of the machine and positioned fore and aft therein having one end adapted to be engaged by said margin stop block and the other end adapted to be moved into the plane of oscillation of said arm when said locking lever is engaged by the margin stop, means operable from the keyboard adapted to swing said locking lever in a vertical plane whereby the rear end thereof is carried out of the path of travel of the margin stop blocks and

- the forward end thereof raised out of the path of travel of said arm connected with said universal rock-shaft, and means for restoring the parts to normal position.
8. In a typewriting machine, the combination with a platen carriage, of a margin stop mounted thereon, a relatively fixed part mounted behind said carriage, a buffer in said part, and a movable stop normally in the path of travel of said margin stop adapted to be engaged thereby and silently arrested by the buffer in said part.
9. In a typewriting machine, the combination with a platen carriage, of a margin stop mounted thereon, an abutment mounted behind said carriage, a buffer in said abutment, a movable stop normally in the path of travel of said margin stop adapted to be engaged thereby and silently arrested by the buffer in said abutment, and means operable from the keyboard for moving said stop out of the path of travel of the margin stop, whereupon said buffer will return the stop to normal position.
10. In a typewriting machine, the combination with the platen carriage, of a stop block mounted upon said platen carriage and adjustable thereon, a casing arranged upon a fixed portion of the machine adjacent said carriage, a plunger having limited reciprocal movement located within said casing, a washer formed of a relatively soft material mounted upon said plunger, a spring adjustably mounted within said casing and urging said plunger to outward movement, said spring being constructed to be compressed less than the amount of space between adjacent teeth of the carriage rack when said plunger is engaged by said stop block during the return movement of the carriage to arrest the return movement of the latter.
11. In a typewriting machine, the combination with the platen carriage, of a rack bar mounted thereon, a margin stop block 45 adjustably mounted upon said rack bar, a casing mounted upon a fixed portion of the machine, a plunger mounted to slide in said casing and projecting therefrom, said casing being arranged in such position that the 50 plunger will be engaged by said margin stop block during the returning of the carriage into a position to begin a new line of writing, a spring located within said casing and urging the plunger to outward movement, 55 cushioning means interposed between said spring and said plunger, and means for adjusting said spring within said casing, said spring when said plunger is engaged by said stop block being adapted to be compressed to 60 an extent less than the space between adjacent teeth of the carriage feed rack.
12. In a typewriting machine, the combination with the platen carriage of a rack bar mounted thereon, a margin stop block ad- 65 justably mounted upon said rack, a spring-pressed plunger adapted to cushion the returning movement of the carriage, and a line-locking lever having a portion thereof interposed between said stop block and said 70 plunger and adapted to be pressed against the latter by the stop block when the carriage returns to begin a new line of writing.

In testimony whereof I affix my signature, in the presence of two witnesses.

JOSEPH ALBERT RONCHETTI.
